UNITED STATES PATENT OFFICE.

ESTELL M. BLACK, OF HARPER'S FERRY, WEST VIRGINIA.

DESIGN FOR A SPOON.

SPECIFICATION forming part of Design No. 21,920, dated October 25, 1892.

Application filed August 30, 1892. Serial No. 444,583. Term of patent 3½ years.

To all whom it may concern:

Be it known that I, ESTELL M. BLACK, a citizen of the United States, residing at Harper's Ferry, in the county of Jefferson and State of West Virginia, have invented certain new and useful Improvements in Designs for Spoons, of which the following is a specification.

My design consists of a spoon having a peculiar configuration of handle, a representation of what is known as "Jefferson's Rock" at the upper end thereof, and in the bowl of the spoon a representation of John Brown's Fort, the whole being designed as a Harper's Ferry spoon.

The accompanying drawing represents a top plan view of my spoon.

The bowl A of the spoon is of well-known

shape or configuration and has therein a representation of the old fort known as "John Brown's Fort." The handle B is of irregular shape, and on the shank or intermediate portion thereof is a space C, and the upper end of the handle is formed with the enlargement D, of the proper shape to receive the representation E of Jefferson's Rock, all as clearly shown.

I claim—

The design for spoons herein shown and described.

In testimony whereof I affix my signature in the presence of two witnesses.

ESTELL M. BLACK.
